DESIGN FOR A WHEEL WEIGHT TOOL

Henry C. Schildmeier, Indianapolis, Ind.

Application December 19, 1946, Serial No. 135,619

Term of patent 14 years

(Cl. D54—13)

To all whom it may concern:

Be it known that I, Henry C. Schildmeier, a citizen of the United States and a resident of Indianapolis, county of Marion, and State of Indiana, have invented a new, original, and ornamental Design for a Wheel Weight Tool, of which the following is a specification, reference being had to the accompanying drawing, forming part thereof.

In the drawing Fig. 1 is a side elevation of a wheel weight tool, showing my new design, and Fig. 2 is an end elevation thereof.

I claim:

The ornamental design for a wheel weight tool, as shown.

HENRY C. SCHILDMIEIER.
